(57) **CLAIM**

The ornamental design for a pen, as shown and described.

DESCRIPTION

FIG. 1 is a front perspective view of a pen showing my new design;

FIG. 2 is a lower front left perspective view thereof;

FIG. 3 is a front elevation view thereof;

FIG. 4 is an enlarged top plan view thereof;

FIG. 5 is a rear elevation view thereof;

FIG. 6 is a left side elevation view thereof;

FIG. 7 is an enlarged bottom plan view thereof; and,

FIG. 8 is a right side elevation view thereof.

The broken lines shown in FIGS. 4 and 5 illustrate environmental subject matter and form no part of the claimed design.
